CLAIM

The ornamental design for a device mount as shown and described.

DESCRIPTION

FIG. 1 is a first perspective view of a device mount shown in a first environment of use;

FIG. 2 is a second perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and

FIG. 8 is a bottom view thereof.

FIG. 9 is a first perspective view of the device mount of FIG. 1 shown without surface shading;

FIG. 10 is a second perspective view thereof;

FIG. 11 is a front view thereof;

FIG. 12 is a back view thereof;

FIG. 13 is a first side view thereof;

FIG. 14 is a second side view thereof;

FIG. 15 is a top view thereof; and

FIG. 16 is a bottom view thereof.

FIG. 17 is a first perspective view of the device mount of FIG. 1 shown in a second environment of use;

FIG. 18 is a second perspective view thereof;

FIG. 19 is a front view thereof;

FIG. 20 is a back view thereof;

FIG. 21 is a first side view thereof;

FIG. 22 is a second side view thereof;

FIG. 23 is a top view thereof; and

FIG. 24 is a bottom view thereof.

FIG. 25 is a first perspective view of the device mount of FIG. 1 shown in a third environment of use;

FIG. 26 is a second perspective view thereof;

FIG. 27 is a front view thereof;

FIG. 28 is a back view thereof;

FIG. 29 is a first side view thereof;

FIG. 30 is a second side view thereof;

FIG. 31 is a top view thereof; and

FIG. 32 is a bottom view thereof.
